(57) **CLAIM**

The ornamental design for an escutcheon, as shown and described.

DESCRIPTION

FIG. 1 is a perspective view of an escutcheon showing a first embodiment of our new design;

FIG. 2 is a front elevation view of the escutcheon as shown in FIG. 1;

FIG. 3 is a rear elevation view of the escutcheon as shown in FIG. 1;

FIG. 4 is a left side elevation view of the escutcheon as shown in FIG. 1, the right side view of which is a mirror image of the left side view;

FIG. 5 is a top plan view of the escutcheon as shown in FIG. 1;

FIG. 6 is a bottom plan view of the escutcheon as shown in FIG. 1;

FIG. 7 is a perspective view of the escutcheon as shown in FIG. 1 with environmental features of a door and door hardware shown;

FIG. 8 is a perspective view of an escutcheon showing a second embodiment of our new design;

FIG. 9 is a front elevation view of the escutcheon as shown in FIG. 8;

FIG. 10 is a rear elevation view of the escutcheon as shown in FIG. 8;
FIG. 11 is a left side elevation view of the escutcheon as shown in FIG. 8, the right side view of which is a mirror image of the left side view;
FIG. 12 is a top plan view of the escutcheon as shown in FIG. 8;
FIG. 13 is a bottom plan view of the escutcheon as shown in FIG. 8;
FIG. 14 is a perspective view of the escutcheon as shown in FIG. 8 with environmental features of a door and door hardware shown;
FIG. 15 is a perspective view of an escutcheon showing an a third embodiment of our new design;
FIG. 16 is a front elevation view of the escutcheon as shown in FIG. 15;
FIG. 17 is a rear elevation view of the escutcheon as shown in FIG. 15;
FIG. 18 is a right side elevation view of the escutcheon as shown in FIG. 15, the left side view of which is a mirror image of the right side view;
FIG. 19 is a top plan view of the escutcheon as shown in FIG. 15;
FIG. 20 is a bottom plan view of the escutcheon as shown in FIG. 15;

FIG. 21 is a perspective view of the escutcheon as shown in FIG. 15 with environmental features of a door and door hardware shown;
FIG. 22 is a perspective view of an escutcheon showing a fourth embodiment of our new design;
FIG. 23 is a front elevation view of the escutcheon as shown in FIG. 22;
FIG. 24 is a rear elevation view of the escutcheon as shown in FIG. 22;
FIG. 25 is a right side elevation view of the escutcheon as shown in FIG. 22, the left side view of which is a mirror image of the right side view;
FIG. 26 is a top plan view of the escutcheon as shown in FIG. 22;
FIG. 27 is a bottom plan view of the escutcheon as shown in FIG. 22; and,
FIG. 28 is a perspective view of the escutcheon as shown in FIG. 22 with environmental features of a door and door hardware shown.
The broken lines showing a back panel and indentations are included for the purpose of illustrating environmental structure and forms no part of the claimed design.
